SURFACE ORNAMENTATION.

No. 16,385.

Patented Nov. 17, 1885.

UNITED STATES PATENT OFFICE.

FREDERICK MANKEY, OF WILLIAMSPORT, PENNSYLVANIA.

DESIGN FOR SURFACE ORNAMENTATION.

SPECIFICATION forming part of Design No. 16,385, dated November 17, 1885,

Application filed October 1, 1885. Serial No. 178,776. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification.

My design consists in a series of zigzag bars or elevations, A, upon the surface, with intermediate channels, B, between said bars. The said bars are disposed relatively parallel, as shown, and are rounded or curved on their upper sides. On the surfaces of said bars may appear a different grain marking from that which appears on the surface of the intermediate channels, B.

I claim as my invention—

The design for surface ornamentation of walls, &c., substantially as herein shown and described, which consists of the zigzag bars or elevations A, arranged relatively parallel, and intermediate channels, B, the surfaces of said bars showing a different grain marking from that which appears on the surfaces of said channels.

FREDERICK MANKEY.
